UNITED STATES PATENT OFFICE.

DANIEL H. TEAS, OF NEW HAVEN, CONNECTICUT, ASSIGNOR TO NILES-BEMENT-POND COMPANY, OF JERSEY CITY, NEW JERSEY.

LATHE-DRIVER.

SPECIFICATION forming part of Letters Patent No. 770,546, dated September 20, 1904.

Application filed March 7, 1904. Serial No. 196,794. (No model.)

To all whom it may concern:

Be it known that I, DANIEL H. TEAS, a citizen of the United States, residing at New Haven, New Haven county, Connecticut, (post-office address 64 Spring street, New Haven, Connecticut,) have invented certain new and useful Improvements in Lathe-Drivers, of which the following is a specification.

In the turning of steel - tired car - wheels while upon their axles great difficulty has been experienced in getting a satisfactory driving grip upon the work without bringing undesired bending strains upon the axle. There is a class of lathes specially devised for this work and embodying a central tubular spindle with a chuck on each end, as will be seen in Cullen and See's patent, No. 312,615, of February 24, 1885, in which lathe the driving was designed to be done from the face-plates referred to. In certain modifications of the lathe referred to non-driven chucks were provided at the outer ends of the axle to grip and steady the wheels. The present construction is designed to still further improve upon lathes of this character, and the improvements will be readily understood from the following description, taken in connection with the accompanying drawings, in which—

Figure 1 is a vertical longitudinal section of the central hollow driving-spindle and the outside chucks provided with my improved drivers; Fig. 2, a side elevation, on an enlarged scale, of the chucks dealing with one of the wheels of the pair; Fig. 3, a plan of one of the drivers; Fig. 4, a side view of one of the drivers; Fig. 5, a plan of one of the chuck-jaws, and Fig. 6 a perspective view of one of the chuck-jaws.

In the drawings, 1 indicates the hollow spindle; 2, the face-plates or chucks on its opposite ends, lying near the inner faces of the car-wheels; 3, the central gear on the spindle, by means of which power is applied to turn it, this gear, the spindle, and the chucks on the ends of the spindle being usually gapped to permit the wheeled axle to be gotten into place in the lathe; 4, the chucks at the outer faces of the car-wheels; 5, the chuck-jaws on

these outer chucks, the same being intended, preferably, to be adjusted outwardly, so as to 50 take a grip within the outward projection of the tire of the car-wheel; 6, a subjaw mounted in each of the chuck-jaws 5 and adapted for movement toward and against the edge of the tire; 7, a wedge crossing the chuck-jaw and 55 engaging behind the subjaw 6 and serving when adjusted to bring the subjaw into proper position against the edge of the tire; 8, a series of abutments projecting outwardly from the face-plates or chucks 2 and presenting driving-shoulders forwardly with reference to the direction of rotation of the work; 9, a thrust-piece having its heel seated against the abutment 8, the thrust-piece projecting diagonally from the abutment toward the inner face of 60 the wheel-tire; 10, a dog having its heel pivoted to the forward end of the thrust-piece and having a serrated gripping-face presented against the inner face of the tire, and 11 a jack-screw interposed between the rear face 65 of the dog and the outer face-plate 2 and serving to force the dog to the car-wheel.

It is preferred that each of the outside chucks 4 have a plurality of jaws, and it is preferred that the inner chucks be provided 75 with a corresponding number of the dogs. Whatever be the number of jaws and dogs, they should be angularly disposed, so that a chuck-jaw will be opposite a dog.

The chucks 4 may be of ordinary construction, their chuck-jaws 5 being radially adjustable in the manner usual in chucks, Fig. 2 showing the heads of the usual radially-disposed jaw-adjusting screws projecting outwardly from the periphery of the chuck. In 85 other words, the jaws 5 are to be the jaws of an otherwise ordinary chuck and arranged for radial adjustment as usual. The peculiarities of the chuck-jaws are illustrated in Figs. 5 and 6, in which it will be seen that the outer 90 portion of the nose of the jaw is serrated. This serrated portion makes engagement outwardly with the bore of the tire where the tire projects outwardly from the wheel center. The chuck-jaw is also provided with the 95 subjaw 6, adapted to be forced against the

outer face of the tire by means of the wedge 7. The peculiar chuck-jaws may be originally constructed to form the jaws of the chuck, or if a chuck with ordinary jaws be employed 5 they may be built out by having such structures as illustrated in Figs. 5 and 6 bolted to them by bolts disposed as indicated by the views of their heads, appearing as circles in Fig. 5 and as ellipses in the perspective view 10 seen at Fig. 6.

The subjaws of the chuck-jaws should be adjusted to a proper normal bearing against the tire without bringing undue disturbing strains upon the wheels and axles. When this has been 15 done, then the jack-screws should be adjusted to bring the dogs forcibly against the inner faces of the tires. The result of this arrangement is that each tire is subjected to a powerful driving grip to almost any extent desired without 20 exerting disturbing strains upon the wheels or axle. The dogs 10 are made double-faced, so that either face may be used for gripping, and countersinks in the serrated faces of the dogs provide for the heads of the 25 jack-screws. My preference is to employ the adjustable chuck-jaws on the outer faces of the tires while the dogs engage the inner faces rather than that the arrangement shall be reversed, the main point, however, being that a 30 given tire, while having its tread and flange exposed for turning, is powerfully gripped sidewise by opposing agents not tending to bring disturbing strains upon the tire to throw it out of true or to spring the axle. In the 35 selected example the driving power is applied through driven chucks or face-plates at the inner faces of the tires, and the dogs are appropriately placed upon these chucks or face-plates instead of the outside ones, it being obvious 40 that the dogs should be upon the chucks or face-plates to which the driving power is applied.

I claim as my invention—

1. In a lathe-driver, the combination, substantially as set forth, of a first face-plate and a second face-plate arranged to receive a tired car-wheel between them, a jaw carried by the first face-plate and arranged to be adjusted toward and against the tire, a dog to be seated 45 against the tire opposite said jaw and between the tire and the second face-plate, an abutment carried by the second face-plate for urging the dog in the driving direction of angular motion, and means disposed between the dog and second face-plate to force the dog to the tire.

2. In a lathe-driver, the combination, substantially as set forth, of a first face-plate and a second face-plate arranged to receive a tired car-wheel between them, a plurality of jaws carried by the first face-plate and arranged to be adjusted toward and against the tire, a dog to be seated against the tire opposite each of said jaws and between the tire and the second face-plate, abutments carried by the second

face-plate for urging the dogs in the driving direction of angular motion, and means disposed between the dogs and second face-plate to force the dogs to the tire.

3. In a lathe-driver, the combination, substantially as set forth, of a first face-plate and a second face-plate arranged to receive a tired car-wheel between them, a jaw carried by the first face-plate and arranged for radial adjustment, a subjaw carried by the jaw and arranged to be adjusted toward and against the tire, a dog to be seated against the tire opposite said subjaw and between the tire and the second face-plate, an abutment carried by the second face-plate for urging the dog in the driving direction of angular motion, and means disposed between the dog and second face-plate to force the dog to the tire.

4. In a lathe-driver, the combination, substantially as set forth, of a first face-plate and a second face-plate arranged to receive a tired car-wheel between them, a jaw carried by the first face-plate and arranged to be adjusted toward and against the tire, a dog to be seated against the tire opposite said jaw and between the tire and the second face-plate, an abutment carried by the second face-plate for urging the dog in the driving direction of angular motion, and a jack-screw interposed between the dog and second face-plate to force the dog to the tire.

5. In a lathe-driver, the combination, substantially as set forth, of a first face-plate and a second face-plate arranged to receive a tired car-wheel between them, a jaw carried by the first face-plate and arranged to be adjusted toward and against the tire, a dog to be seated against the tire opposite said jaw and between the tire and the second face-plate, an abutment carried by the second face-plate for urging the dog in the driving direction of angular motion, a thrust-piece disposed between the dog and the abutment, and means disposed between the dog and second face-plate to force the dog to the tire.

6. In a lathe-driver, the combination, substantially as set forth, of a first face-plate and a second face-plate arranged to receive a tired car-wheel between them, a jaw carried by the first face-plate and arranged to be adjusted toward and against the tire, a dog to be seated against the tire opposite said jaw and between the tire and the second face-plate, an abutment carried by the second face-plate for urging the dog in the driving direction of angular motion, a thrust-piece pivoted to the rear end of the dog and having its heel engaging said abutment, and means disposed between the dog and second face-plate to force the dog to the tire.

7. In a lathe-driver, the combination, substantially as set forth, of a first face-plate and a second face-plate arranged to receive a tired car-wheel between them, a jaw carried by the

first face-plate and arranged to be adjusted toward and against the tire, a dog to be seated against the tire opposite said jaw and between the tire and the second face-plate and having 5 opposite serrated faces, a thrust-piece pivoted to the rear end of the dog, an abutment carried by the second face-plate for urging the thrust-piece in the driving direction of angular motion, and means disposed between the 10 dog and second face-plate to force the dog to the tire.

8. In a lathe, the combination, substantially as set forth, of a hollow spindle adapted for disposition upon a car-axle between a pair of 15 car-wheels fast upon the axle, a face-plate on each end of said spindle, face-plates in position to stand near the outer faces of the

wheels, chuck-jaws carried by said last-mentioned face-plates, subjaws carried by said chuck-jaws and adapted for adjustment toward and against the car-wheel, serrated dogs carried by the first-mentioned face-plates and adapted to engage the inner faces of the car-wheels, abutments carried by the first-mentioned face-plates to urge the dogs in the driving direction of angular motion, and jack-screws disposed between the dogs and the first-mentioned face-plates to force the dogs against the car-wheels. 20 25
